ATTORNEY

UNITED STATES PATENT OFFICE.

LEAMAN S. HARVEY, OF WATERBURY, CONNECTICUT.

DESIGN FOR COMBINED TAIL LIGHT AND SLOW AND STOP SIGNAL.

Application filed September 11, 1924. Serial No. 10,741. Term of patent 14 years.

To all whom it may concern:

Be it known that I, LEAMAN S. HARVEY, a citizen of the United States, residing at Waterbury, in the county of New Haven and State of Connecticut, have invented a new, original, and ornamental Design for Combined Tail Light and Slow and Stop Signal, of which the following is a specification, reference being had to the accompanying drawing, forming part thereof.

In this drawing:

Fig. 1 is a front view of the combined tail light and slow and stop signal.

Fig. 2 is a side view of the same.

I claim:

The ornamental design for the combined tail light and slow and stop signal as shown.

LEAMAN S. HARVEY.
